UNITED STATES PATENT OFFICE.

HENRY F. BUETTNER, OF HAMPTON, IOWA.

ADJUSTABLE SUPPORTING BRACKET.

Application filed December 12, 1924. Serial No. 755,520.

To all whom it may concern:

Be it known that I, HENRY F. BUETTNER, a citizen of the United States, residing at Hampton, in the county of Franklin and 5 State of Iowa, have invented certain new and useful Improvements in Adjustable Supporting Brackets, of which the following is a specification.

This invention relates to swinging and adjustable supports or brackets for typewriters, and for like purposes, and has for one of 10 its objects to provide a simply constructed device of this character which may be attached to a stationary support such as a desk, table, or the like, and which may be 15 adjusted vertically and rotatively and clamped in adjusted position.

With these and other objects in view the invention consists in certain novel features 20 of construction as hereinafter shown and described and then specifically pointed out in the claims, and in the drawings illustrative of the preferred embodiment of the invention.

25 Fig. 1 is a side elevation of the improved device.

Fig. 2 is a bottom plan view, partly in section.

30 Fig. 3 is a section on the line 3—3 of Fig. 1.

Fig. 4 is a sectional detail of the adjustable coupling between the bracket and platform.

The improved device includes a supporting or base plate 10 adapted to be attached 35 to a stationary support, for instance a desk, a portion of which is indicated at 11.

Extending from the plate 10 near its upper portion is a socket or apertured lug 12, 40 and extending from the base plate near its lower portion is another socket or lug 13, the latter being of the split form and having a clamp screw 14.

The bracket portion of the improved device 45 comprises an upper horizontal portion 15 and an obliquely directed bracing portion 16, preferably formed of sections of tubing united by brazing or electrical welding, but may be solid rods.

50 A pin 17 depends from the bracket member 15 and engages in the bore of the lug 12, while a similar pin 18 depends from the brace 16 and engages in the bore of the lug 13.

55 By this means the bracket device is supported to swing laterally, and may be

clamped in position by actuating the clamp screw 14.

Attached to or formed integral with the member 15 of the bracket is an internally 60 threaded sleeve 19 to receive a threaded standard 20, the latter held in adjusted position by a jamb nut 21.

Attached to or formed integral with the standard 20 and spaced below the upper end thereof is a laterally directed head member 22, and riveted or otherwise rigidly attached at 23 to the head member is a relatively 65 large supporting plate 24.

The projecting upper ends of the standard 70 20 extends through the plate 24 and is upset as shown to assist in holding the plate in position and supplementing the holding force of the rivets 23. The union between the pin 20 and the plate 24 is thus materially strengthened and the tendency to work 75 loose under strain obviated.

Riveted or otherwise rigidly attached at 80 25 to the supporting plate is a platform member 26 to support a typewriter a portion of the base of the latter being represented conventionally at 27.

By this means a convenient and simply 85 constructed device is produced whereby a typewriter or other device or object may be supported in position relative to a desk, table, or other support, which may be adjusted vertically, moved laterally or rotatively, and locked in adjusted position.

The device may be constructed of any required 90 size or of any desired material.

The preferred embodiment of the invention 95 is disclosed in the drawings and set forth in the specification, but it will be understood that modifications within the scope of the claimed invention may be made in the construction without departing from the principle of the invention or sacrificing any of its advantages.

Having thus described the invention, what 100 is claimed is:

1. A device of the class described comprising a base member adapted to be attached to a support and having spaced vertically aligned sockets, a bracket device having 105 depending pins engaging respectively in said sockets and with an internally threaded sleeve at the free end, a threaded stud engaging in said sleeve, a laterally directed head carried by said stud and spaced below 110 the upper end thereof, a supporting plate apertured to receive the portions of the stud

above the head and bearing on the head and attached thereto, and a platform supported on said plate.

2. A device of the class described including a bracket adapted to be attached to a support and having an internally threaded sleeve at the outer end, a threaded stud engaging in said sleeve and having a lateral head spaced from the upper end, a supporting plate apertured to receive the portion of the stud above the head and bearing on the head and attached thereto, said plate adapted to support a platform member.

3. A device of the class described including a bracket adapted to be attached to a support and having a sleeve at the other end, a stud movably engaging in said sleeve and having a lateral head spaced from the upper end, and a supporting plate apertured to receive the portion of the stud above the head and bearing on the head and attached thereto, said plate adapted to support a platform member. 15 20

In testimony whereof, I affix my signature hereto.

HENRY F. BUETTNER.
